UNITED STATES PATENT OFFICE.

OLIVER B. WOODROW, OF NEWTON, IOWA.

GEAR-DRIVE FOR WRINGERS.

1,118,991.

Specification of Letters Patent.

Patented Dec. 1, 1914.

Application filed September 10, 1909. Serial No. 517,029.

To all whom it may concern:

Be it known that I, OLIVER B. WOODROW, a citizen of the United States, residing at Newton, in the county of Jasper and State 5 of Iowa, have invented a certain new and useful Gear-Drive for Wringer, of which the following is a specification.

The objects of my invention are to provide an operating device of the class described, of 10 simple, durable and inexpensive construction so arranged that the shaft which operates the wringer may be continuously rotated in one direction and the wringer be made to move in either direction so that in 15 the event that clothes should become wound upon one of the wringer rollers, the movement of the rollers may be quickly stopped or reversed.

My invention consists in the construction, 20 arrangement, and combination of the various parts of the device, whereby the objects contemplated are attained, as hereinafter more fully set forth, pointed out in my claims, and illustrated in the accompanying 25 drawings, in which—

Figure 1 shows a top or plan view of a washing machine and wringer having my improvements applied thereto. Fig. 2 shows a side elevation of same to illustrate the 30 gearing devices for the wringer and washing machine, and Fig. 3 shows a view similar to Fig. 2 taken from a position at right-angles to that of Fig. 2.

Referring to the accompanying drawings, 35 I have used the reference numeral 10 to indicate the body of the washing machine or other device to which my improvement is applied, 11 indicates the supporting legs therefor, and 12 indicates a platform arranged between the supporting legs and beneath the body. Mounted upon the platform 12 is an electric motor 13 provided with a small pulley 14. Mounted in suitable bearings 15 on the platform 12 is a rotatable 40 shaft 16. Fixed to said shaft is a pulley 17. Loosely mounted on the shaft 16 adjacent to the pulley 17 is a gear wheel 18. The said cog-wheel 18 is arranged in mesh with a large cog-wheel 24 which is mounted upon a 45 shaft 25 and which has a pitman 26 connected with it, which pitman is pivoted to a lever 27 and said lever is designed to operate the washing machine or other device to which my improvement is applied. Mounted upon opposite end of shaft 16 is a pulley 50 55 28 having connected thereto a belt 34 and

the latter being operatively connected to the wringer reversing mechanism.

The device for operating the wringer, 60 comprises a shaft 39 mounted on the machine body and provided at one end with a pulley 40 having the belt 34 applied thereto. On this shaft 39 is a small pinion 41. Mounted on the machine body adjacent to the shaft 39 is a shaft 42 having thereon the 65 large pinion 43 in mesh with the small pinion 41. Rotatably mounted on the shaft 42 is a sleeve 44 having on one end a clutch member 45, and fixed to its other end is a sprocket wheel 46. Rotatably mounted on the other end of the shaft 42 is a similar 70 sleeve 47 having the clutch member 48 at one end and a sprocket wheel 49 at the other. Slidingly and non-rotatably mounted upon the shaft 42, between the clutch members 45 75 and 48, is a hub 50 having clutch members at its ends so arranged that the hub may be placed in position out of engagement with both of said clutch devices or it may be thrown into engagement with either one of 80 them. This is done by means of a lever 51 having a pin 52 at its lower end and a crank shaft 53 extended under the machine body. This crank has a slot 54 in its upper end to receive the pin 52, and a handle 55 at its 85 other end extended upwardly alongside of the machine body so that said hub 50 may be shifted by an operator standing on the side of the machine opposite from the wringer.

The wringer proper is indicated by the 90 reference numeral 56 and is provided with two rollers, the upper one having its shaft 57 extended outwardly and provided with a sprocket wheel 58 connected by a chain 59 95 with the sprocket wheel 49. The shaft of the lower roller is extended outwardly in the opposite direction from the shaft 57 and is indicated by the numeral 60. Shafts 57 and 60 are provided with rollers 57^a and 60^a 100 respectively. It has a sprocket wheel 61 thereon connected by a sprocket wheel 62 with the sprocket wheel 46. By means of this construction, it is obvious that so long as the belt 34 is operated, the shaft 42 will 105 be continuously rotated in one direction. When the hub 50 is shifted to one limit of its movement, the sleeve 44 will be rotated and the wringer will be turned in one direction, and when the hub 50 is shifted to its 110 opposite limit of movement, the sleeve 47 will be rotated and the wringer will be op-

erated in a reverse direction. By this arrangement, the wringer may be readily and easily controlled and its movement can be stopped almost instantly without the necessity of stopping the motor.

In operating the wringer the motor is started which in turn operates the pulley 40 thereto the mechanism as before described. During the rotation of the pulley 40, the 10 wringer shaft is in continual rotation, and to operate the wringer, the operator stands in a position adjacent to the lever 55, whereby upon the manipulation of said lever, the wringer may be quickly and easily stopped 15 or reversed in either direction. It is obvious that all the mechanism is of a simple and inexpensive construction, and that the parts are not liable to get out of order.

I claim as my invention:

- 20 1. In a device of the class described, the combination of two roller shafts, rollers thereon in frictional engagement with one another, a gearing device connected with each, a shaft for operating the roller shafts, 25 means for continuously rotating the latter shaft in one direction, two sleeves rotatably mounted on the latter shaft, each sleeve being provided with a gearing device operatively connected with the gearing devices on 30 said shafts, each sleeve also being provided with a clutch member on the adjacent ends of said sleeves, a hub slidably and non-rotatably mounted on the shaft between said clutch members, said hub having clutch 35 members at its ends, said hub being designed to be placed between said clutch members of the sleeves or to be placed in engagement with either one of them, a support, and a hand lever passing under said support and

having a vertical hand piece within convenient reach of the operator.

2. In a device of the class described, the combination of two roller shafts, rollers thereon in driving engagement with one another, a driving shaft, means for continuously operating the driving shaft in one direction, two sleeves on the driving shaft, means for operatively connecting said sleeves with the roller shafts, and means interposed between said sleeves for operatively connecting either one of them with the power shaft; said means including a hand lever operative from in front of said rollers.

3. In a device of the class described, the combination of a motor, a shaft, means interposed between the motor and the shaft for driving the latter continuously in one direction, a hub slidably and non-rotatably mounted on the driving shaft and having 55 clutch members at its ends, a lever connected to said hub and extended downwardly, a rock-shaft having one end pivotally and slidably connected with said lever and having an upright handle in front of said power 60 shaft on its other end, two roller shafts, rollers thereon, two sleeves mounted on said power shaft, and each provided with a clutch member, and means connected with each of said sleeves for imparting motion to 65 one of said roller shafts, for the purposes stated.

Des Moines, Iowa, June 29, 1909.

OLIVER B. WOODROW.
